SAFETY PIN OR THE LIKE

Eugene S. Drake, 2836 Kansas Ave.,
South Gate, Calif. 90280

Continuation-in-part of design application Ser. No. 4,284, Oct. 14, 1966, now Patent No. 210,817, dated Apr. 23, 1968. This application May 22, 1967, Ser. No. 7,213

Term of patent 14 years
The portion of the term of the patent subsequent to
Apr. 23, 1982, has been disclaimed

Int. Cl. D2—08

U.S. Cl. D2—413

FIG. 1

FIG. 2

FIG. 3

FIG. 4

FIG. 5

FIG. 6

FIGURE 1 is an upper perspective view of a safety pin or the like, showing my new design in a closed position; FIGURE 2 is a lower perspective view thereof; FIGURE 3 is a side elevational view thereof; FIGURE 4 is a bottom view thereof; FIGURE 5 is a frontal elevational view thereof; and FIGURE 6 is a side elevational view thereof in an opened position.

This application is a continuation-in-part of my co-pending application Ser. No. D. 4,284, filed Oct. 14, 1966, and now Patent No. D. 210,817.

I claim:

The ornamental design for a safety pin or the like, substantially as shown and described.
